UNITED STATES PATENT OFFICE.

ANDREW L. REINER, OF BLUE ISLAND, ILLINOIS.

DESIGN FOR A BRACKET FOR SICKLE-GRINDERS.

SPECIFICATION forming part of Design No. 31,093, dated June 27, 1899.

Application filed June 2, 1899. Serial No. 719,152. Term of patent 7 years.

To all whom it may concern:

Be it known that I, ANDREW L. REINER, a citizen of the United States, residing at Blue Island, in the county of Cook and State of Illinois, have invented and produced a new and original Design for Brackets for Sickle-Grinders, of which the following is a specification, reference being had to the accompanying drawings, forming part thereof.

10 Figure 1 is a side elevation of a bracket for sickle-grinders, showing my design. Fig. 2 is a top edge view of the same.

The leading feature of my design consists in a bracket having end portions and having 15 a curved transverse slot in one end and a longitudinal slot in the other and having raised longitudinal ribs in the side surface and enlarged bosses.

Reference-sign A designates the central 20 boss or hub of the bracket, circular in end view, as shown in Fig. 1, and B C the end

portions; D, the raised ribs, extending longitudinally and centrally of the end portions in the side surface thereof; E, a circular transverse slot, the curves of which are concentric with the axis of boss or hub A; F, the raised boss surrounding said curved slot and which is oblong in end view; G, the longitudinal slot; H, the boss surrounding the same and which is circular in end view; J, a hub 25 or boss in the end of end portion C and which is circular in end view; and K is a lateral extension having a central raised rib constituting a continuation of the raised rib D.

What I claim is—

35

The design for a bracket for sickle-grinders substantially as shown and described.

ANDREW L. REINER.
